Primary Examiner — Prabhakar Deshmukh*(74) Attorney, Agent, or Firm* — Banner & Witcoff, Ltd.**(57) CLAIM**

The ornamental design for a latch and latch keeper, as shown and described.

DESCRIPTION

FIG. 1 is a top, front, left perspective view of a latch and latch keeper showing my new design;

FIG. 2 is an enlarged partial top, front, left perspective view thereof;

FIG. 3 is an enlarged partial bottom, front perspective view thereof;

FIG. 4 is an enlarged exploded top, front, left partial perspective view thereof; and,

FIG. 5 is an enlarged partial bottom, front perspective view of an alternative configuration thereof.

The broken lines showing the remainder of the latch and latch keeper are for environmental purposes only and form no part of the claimed design.
